United States Patent Office

Des. 196,371
Patented Sept. 24, 1963

196,371

PICNIC TABLE OR SIMILAR ARTICLE

Efraim Lieberman, New York, N.Y.
(1840 E. 13th St., Brooklyn 25, N.Y.)

Filed May 3, 1962, Ser. No. 69,962

Term of patent 7 years

(Cl. D33—14)

Fig. 1

Fig. 2

Fig. 3

Fig. 5

Fig. 4

Fig. 6

FIGURE 1 is a perspective view of a picnic table or similar article in open set-up position, showing my new design.

FIGURE 2 is a perspective view showing the device in collapsed portable position.

FIGURE 3 is a rear elevational view, as seen from the rear of FIGURE 1, with the side bags suspended.

FIGURE 4 is an end elevational view.

FIGURE 5 is a top plan view of FIGURE 3.

FIGURE 6 is a bottom plan view of FIGURE 3.

I claim:

The ornamental design for a picnic table or similar article, substantially as shown and described.
